UNITED STATES PATENT OFFICE.

ALBERT HOAG, OF PEARL, VERMONT.

HAND SEED-PLANTER.

SPECIFICATION forming part of Letters Patent No. 295,762, dated March 25, 1884.

Application filed November 14, 1883. (No model.)

To all whom it may concern:

Be it known that I, ALBERT HOAG, a citizen of the United States, residing at Pearl, in the county of Grand Isle and State of Vermont, have invented certain new and useful Improvements in Hand Seed-Planters; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a rear elevation of my device. Fig. 2 is a front view of the same with the lower portion of its casing partly broken away. Fig. 3 is a side elevation with the casing partly broken away. Fig. 4 is a longitudinal sectional view. Fig. 5 is a transverse sectional view; and Figs. 6, 7, 8, and 9 are detail views.

This invention has relation to improvements in hand seed-planters; and it consists in the construction and novel arrangement of devices, as will be hereinafter more fully set forth, and particularly pointed out in the claims appended.

In the accompanying drawings, the letter A designates a metallic skeleton frame, usually made of cast-iron, and consisting of the shoe portion B, having the concave passage a and sides b. From the shoe lateral arms c extend upward to the top of the frame, and are connected by the transverse bars d and e. The side bars or arms, c, are formed with flanges f, over which the edge lips g of the sheet-metal front wall, C, of the seed-chamber D are bent and secured. This wall C is of curved or partial cylindrical form. E represents the plane sheet-metal back wall of the chamber, which also engages the frame, being secured at its ends, one end being passed in front of the side flanges, f, and back of the lugs l of the frame, and the other end being secured between the flanges f and the transverse bar e.

F indicates the spring-plate of the shoe. At its upper end this plate is provided with two or more perforations, arranged on each side in vertical series. The plate is riveted to the transverse bar G, which is formed with

end lugs, h, engaging bearings in the edges of the sides b of the shoe, and arms k, which extend toward the back of the shoe, to form guides for the plunger. This bar is riveted 55 to the side walls of the shoe.

H indicates the plunger, having a shank of cast-iron, composed of vertical bars m and transverse connections n. Along the center of the upper portion of the shank is the governing-slot s, which engages the post or guide-stud p, which is on the transverse bar e of the main frame. This post is provided with a head, r, which is connected to it by a screw, t. The shank of the plunger may be made in 65 several sections, if desirable. The lower portion of the shank above the plunger-plate is formed with an oblique cam-bar, v, of somewhat rounded form, and designed to engage a notch-bearing, w, in the projection a' of the 70 valve K, so that when the plunger is moved up and down the valve will be operated. The valve K is pivoted in the valve-chamber casting L, which is secured to the lugs l of the main frame. The top b' of the valve-chamber 75 casting is made concave, and has an opening leading to the seed-chamber c' in the valve.

N represents the clearing-brush, which is secured to the top of the valve-chamber.

P indicates a sheet-metal tube leading from 80 the lower opening in the valve-chamber to the shoe.

In the valve is located an adjustable block, d', having an edge-serrated shank, e', which is designed to engage a tooth, g', of the valve-body. This block is adjustable, to increase 85 or lessen the size of the seed-chamber in the valve. It is held in position by means of a wire, z'.

The shoe of the planter being open at top 90 and separated from the base of the seed-chamber by an interval, the operator can see, the contents of the shoe at any time.

Having described this invention, what I claim, and desire to secure by Letters Patent, 95 is—

1. The combination, with the skeleton frame and the seed-chamber thereon, of the open-top shoe at the lower end of the frame, and separated from the base of the seed-chamber by an 100 interval, so that its contents can be inspected, substantially as specified.

2. The combination, with the shoe and spring-plate, of the transverse bar to which the spring-plate is riveted, having arms extending toward the back of the shoe to serve as guides for the plunger.

3. The feed-block located in the valve, and having a flat shank made with a serrated edge, in combination with a tooth of the valve-body and a holding device, whereby the feed-block

can be adjusted to increase or lessen the size of the seed-chamber in the valve, substantially as specified.

In testimony whereof I affix my signature in presence of two witnesses.

ALBERT HOAG.

Witnesses:

MARY L. ROBINSON,
H. HARRINGTON.
